UNITED STATES PATENT OFFICE.

MATTHEW DUVEN, OF ALTO, WISCONSIN.

LATCH.

SPECIFICATION forming part of Letters Patent No. 626,530, dated June 6, 1899.

Application filed January 26, 1899. Serial No. 703,485. (No model.)

To all whom it may concern:

Be it known that I, MATTHEW DUVEN, of Alto, in the county of Fond du Lac and State of Wisconsin, have invented certain new and useful Improvements in Latches; and I do hereby declare the following to be a full, clear, and exact description of the invention, such as will enable others skilled in the art to which it pertains to make and use it, reference being had to the accompanying drawings, which form part of this specification.

My invention relates to improvements in door latches and holders, and is especially intended to be used in connection with barn-doors, though it is adapted to be used for other doors, windows, or gates without departing from the spirit of my invention.

The object of my invention is to provide an improved latch and holder, hereinafter fully shown and described, and particularly pointed out in the claims.

In the accompanying drawings, Figure 1 is a perspective view of a latch and holder embodying my invention, the door and door-frame being shown in dotted lines. Fig. 2 is a detached perspective view of the horizontal handle. Fig. 3 is a detached perspective view of the latch.

The door A and the door-frame or side of the barn B are shown in dotted lines. At one side of the door is situated a horizontal handle C, having one end provided with the diverging arms D, the ends of which are connected by a web E. The extremities of these arms are provided with bolt-openings, and the opposite ends of the handle are turned inward and provided with a screw for attachment to the door. The web is provided, intermediate its ends with an elongated socket e', having its inner end open, and forms a bearing for the latch F. This latch F consists of a handle H, preferably L shape in form, which passes through an opening in the barn-door. A transversely-extending bearing G is at the end of this handle, and projecting outward horizontally from each side of this bearing are the arms I, provided with the shoulders J, adapted to coact with and to catch against the shoulders K of the catch L. Extending upward from the end of the bearing are the arms or shoulders M, which rest against the door and hold the latch in its

proper position to pass within the catch L. The handle of the latch by its own gravity holds the catch end of the latch normally upward to coact with the catch upon the door. This catch preferably consists of a plate with an opening N, the ends of the arms forming the opening having inwardly-extending shoulders K to form catches, and these united by a transverse plate O, set in the edge of the door-frame, as shown. In this way the catch is not thrown out of position by the warping or twisting of the door-frame or door. Situated at the opposite side of the door is a vertical handle P, which is recessed at its inner side and receives the handle of the latch within the recess, as clearly shown, whereby the handle is practically out of sight and cannot be operated by being struck by animals, as an ordinary latch can. The lower end of this handle is provided with a pivotal opening Q, through which a screw or bolt passes, and the opposite end of this handle is preferably provided with a horizontal slot R. A bolt S passes through this slot R and through the perforations or openings in one of the arms of the horizontal handle, as shown, serving the double purpose of securing that arm of the horizontal handle and the upper end of the vertical handle in position, and the slot R in the vertical handle enables this to be moved to either side for bringing the handle of the latch properly within the recess of the vertical handle and free from any engagement therewith, which always insures its accurate and positive working. This vertical handle, as shown, is recessed from end to end; but the recessed portion is only necessary at the upper portion for the reception of the latch, it being recessed throughout its length as a saving in material and weight.

The shouldered arms of the latch, as will be seen, extend between the diverging arms of the horizontal latch and are therefore protected, and the latch is journaled through the medium of the web, which connects the ends of these diverging arms, as before stated. One of the latch-arms serves as a medium to throw the latch out of engagement with the catch from that side of the door upon which the horizontal handle is situated, while the handle of the latch within the vertical handle at the opposite side of the door serves by

raising it to throw the latch out of engagement with the catch.

By means of a latch of the construction here shown it is adapted for the right or the left hand side of the door in that when it is at the left-hand side of the door one of the arms is just outside of the diverging arms of the horizontal handle and serves to engage the catch upon the door-frame and the other arm is within the horizontal handle to be operated by the fingers in opening the door, and vice versa, when the latch is placed at the opposite side of the door. It will also be noted that in a construction of this character the horizontal handle serves as a pivotal support for the latch, and the parts are easily and quickly adjusted to a door by simply cutting an opening therein through which the latch may pass.

Having thus described my invention, what I claim, and desire to secure by Letters Patent, is—

1. The combination with a door having a transverse opening, of a horizontal handle situated at one side of the door and having diverging arms, a transverse plate connecting the ends of said diverging arms, a latch extending through the door from the opposite side thereof and journaled intermediate its ends upon the said transverse plate of the horizontal handle, the latching end of the latch projecting in a line between the said diverging arms, and a latching-shoulder in a line drawn between the said diverging arms and at a point outside of the journal of the latch, substantially as described.

2. A latch comprising a horizontal handle provided at one end with inwardly-diverging arms secured to the door and supporting the handle away from the door, a latch passing through the door from the opposite side thereof and having a latching end extending between the diverging arms, whereby the latching end is protected by the horizontal handle and may be operated from either side of the door, substantially as described.

3. A latch comprising a horizontal handle having inwardly-extending diverging arms supporting the handle out of contact with the door, a vertical handle at the opposite side of the door with its upper end above a line drawn through the door between said diverging arms, a latch passing through the door to the opposite side and having its handle between the vertical handle and the door, and its opposite latching end between the diverging arms of the horizontal handle, and a co-

acting latching member situated on a line drawn between the diverging arms, substantially as described.

4. A latch comprising a horizontal handle at one side of the door, a vertical handle at the opposite side of the door, and a latching member comprising a handle situated within the vertical handle and a projecting catching member at the opposite side of the door, substantially as described.

5. A latch comprising a horizontal handle, a vertical handle, the horizontal handle having diverging arms, a latching member comprising a handle situated within the vertical handle, a transverse journal at the end of the latching member's handle, pivoted at a point between the diverging arms of the horizontal handle and provided with a projecting catching member, and a bolt passing through one of the diverging arms of the horizontal handle and the adjacent end of the vertical handle, substantially as described.

6. A latch comprising a latching member having a handle, a transverse pivotal member at the end of the handle provided with a projecting catching member pivoted at one side of the door, a vertical handle at the opposite side of the door provided with a recess at its inner side within which the handle of the latch member is situated, substantially as described.

7. A latch comprising a vertical handle having a recess at its inner side, a latching member provided with a handle situated within the recess, the said handle having a pivotal member at its opposite side with a projecting catching member, the vertical handle having a horizontal slot and a securing bolt or screw passing through the said slot whereby the handle can be moved laterally in respect to the handle of the latching member for the purpose described.

8. A handle for a latch essentially U-shaped, in outline, one end of the handle having inwardly-diverging arms, and a web connecting the ends of the diverging arms, said web provided with a latch-journal, whereby the space between the arms and said web is adapted to receive a latching member, substantially as described.

In testimony whereof I affix my signature in presence of two witnesses.

MATTHEW DUVEN.
